(57) **CLAIM**

The ornamental design for a race track toy set, as shown and described.

DESCRIPTION

FIG. 1 is a top, front and right side perspective view of a race track toy set showing my new design;

FIG. 2 is a bottom, rear and left side perspective view thereof;

FIG. 3 is a top and rear side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 in FIG. 1;

FIG. 11 is an enlarged view of portion 11 in FIG. 1;

FIG. 12 is an enlarged view of portion 12 in FIG. 1;

FIG. 13 is an enlarged view of portion 13 in FIG. 1;

FIG. 14 is an enlarged view of portion 14 in FIG. 4;

FIG. 15 is an enlarged view of portion 15 in FIG. 8;

FIG. 16 is an enlarged view of portion 16 in FIG. 8; and,

FIG. 17 is an enlarged view of portion 17 in FIG. 8.

The evenly dashed broken lines illustrate features of the race track toy set that form no part of the claimed design. The unevenly dashed broken lines define the boundaries of enlarged views and form no part of the claimed design.

1 Claim, 17 Drawing Sheets
